CLAIM

The ornamental design for a contoured housing, as shown and described.

DESCRIPTION

FIG. 1 is a perspective view of a contoured housing showing a first embodiment of our new design;

FIG. 2 is a top plan view thereof;

FIG. 3 is a left side elevational view thereof, the right side being a mirror image thereof;

FIG. 4 is a front elevational view thereof;

FIG. 5 is a rear elevational view thereof;

FIG. 6 is a bottom plan view thereof; and

FIG. 7 is a perspective view of a contoured housing showing a second embodiment of our new design;

FIG. 8 is a top plan view thereof;

FIG. 9 is a left side elevational view thereof, the right side being a mirror image thereof;

FIG. 10 is a bottom plan view thereof;

FIG. 11 is a front elevational view thereof;

FIG. 12 is a rear elevational view thereof;

FIG. 13 is a perspective view of a contoured housing showing a third embodiment of our new design;

FIG. 14 is a left side elevational view thereof, the right side being a mirror image thereof; and,

FIG. 15 is a bottom plan view thereof.

The top plan, front elevational and rear elevational views of the third embodiment are like FIGS. 8, 11, and 12, respectively, of the second embodiment.

The dotted lines shown herein are for illustrative purposes only and form no part of the claimed design.
